UNITED STATES PATENT OFFICE

VICTOR JOSEPH LARAMIE, OF DETROIT, MICHIGAN

MILK-BOTTLE CAP

Application filed March 6, 1929. Serial No. 344,784.

This invention relates to an improved milk bottle cap or stopper which is primarily intended for use in the home and adapted to take the place of the ordinary cardboard cap after the latter has been removed.

It is the customary practice to either puncture the existing cap to remove it or to pull it off by means of finger tab or grip with which it is sometimes provided.

10 This usually disrupts the cap and renders it substantially useless. Many times, the entire contents of the bottle is not used, but the cardboard cap is so misshapen and soiled that it is not convenient for replacement.

15 It is therefore my purpose to provide a permanent closing cap to take the place of the cardboard cap after the latter has been removed, the improved cap being such in construction as to effect a tight closure, to prevent pollution of the milk and to promote desirable sanitary conditions.

20 I am aware of the fact that household caps of this type are not new in the art, broadly stated. In fact, I know that the art is reasonably well developed. At the same time, I am unaware of any household milk bottle cap which is quite as simple as the one herein illustrated and claimed.

25 It follows that my principal aim is to generally improve upon patented and marketed articles of this class by providing one which is made in a single piece and which comprises a single disc and a finger piece carried thereby, whereby to avoid all crevices and projections for accumulation of milk, and to reduce the expense of manufacture and sale to a minimum.

In the drawings:

30 Figure 1 is a top plan view of a milk bottle showing the improved cap in place.

Figure 2 is a fragmentary view of the milk bottle neck with the cap in position thereon.

Figure 3 is a perspective view of the complete article itself.

35 In Figure 2 it will be observed that 4 designates the neck of an ordinary milk bottle which terminates at its top in an outstanding bead 5, and which is formed with an inner annular groove forming a ledge or shoulder as at 6, upon which the ordinary top (not seen) 50 is seated.

The improved household cap is designated generally by the reference character 7 and comprises a polished aluminum or similar light weight metal disc of a uniform diameter to fit snugly within the neck and to rest firmly upon the ledge 6. This is provided on one peripheral leg with a hook shaped finger grip 8. The extremity 9 of the hook terminates in spaced relation to the upper side of the disc to permit a space to exist here for removing accumulation of dust, dirt, or milk. This also gives the finger grip a slightly resilient action, holding the opposite end portion 10 of the hook in firm contact with the adjacent surface of the bead 5 of the bottle.

It is to be noted that this article of manufacture is of utmost simplicity in construction. It is therefore unusually economical for both the manufacturer and the user. Moreover, it is of light weight material, yet sturdy in construction. There are no projections on the surfaces of the disc to provide crevices and portions in which dirt may accumulate. 70 Hence the device is highly sanitary. Consequently, though unusually simple, the device is nevertheless different from prior art devices with which I am familiar. It is thought, however, that persons familiar with articles of this class will be able to obtain a clear understanding of the invention, construction and advantages, after reading the description in conjunction with the drawings. Therefore a more lengthy description 75 is regarded as unnecessary.

Miner changes in the shape, size and rearrangement of details coming within the field of invention claimed may be resorted to, in actual practice, if desired.

I claim:

A bottle cap of the character described, comprising a thin, rigid, metallic disc adapted to seat in the mouth of a milk bottle, and an upwardly, inwardly and downwardly curved rigid metallic finger formed integral with the marginal portion of the disc and extending rearwardly thereover and terminating in spaced opposed relation to the inner portion of said disc.

10 In testimony whereof I affix my signature.

VICTOR JOSEPH LARAMIE.
